UNITED STATES PATENT OFFICE

HARRY J. LEBHERZ, OF FREDERICK, MARYLAND, ASSIGNOR TO THE EVEREDY COMPANY, OF FREDERICK, MARYLAND, A CORPORATION OF MARYLAND

BOTTLE CAPPING THROAT

Application filed March 21, 1930. Serial No. 437,832.

My invention relates broadly to bottle capping tools and more particularly to the capping throat of a bottle capping tool.

One of the objects of my invention is to provide a construction of bottle capping throat for a bottle capping tool in which a crown cap may be readily centered in the capping throat and retained therein preparatory to a capping operation.

10 Another object of my invention is to provide a construction of bottle capping throat having a depending skirt thereon for embracing the peripheral edge of a crown cap preparatory to a bottle capping operation 15 for applying a radially inward uniform thrust upon the peripheral edge of the cap thereby contracting the diameter of the cap and enabling the cap to be retained in a bottle capping position in the capping throat 20 preparatory to a bottle capping operation.

Still another object of my invention is to provide a construction of bottle capping throat having an angularly disposed annular wall forming the inner periphery of the bottle capping throat and serving to contract the diameter of the skirt of a crown cap which is inserted for resiliently retaining the crown cap in bottle capping position preparatory to a bottle capping operation.

30 Other and further objects of my invention reside in the construction of crown cap set forth more fully in the specification hereinafter following by reference to the accompanying drawings, wherein:

35 Figure 1 is a side elevation of a bottle capping tool equipped with the bottle capping throat of my invention; Fig. 2 is a cross-sectional view taken through the bottle capping throat of my invention and illustrating 40 the angularly disposed annular wall forming the inner periphery of the bottle capping throat and illustrating a crown cap preparatory to the insertion thereof in position within the bottle capping throat; Fig. 3 is a cross-sectional view illustrating the crown cap retained in position within the bottle capping throat; Fig. 4 is a cross-sectional view 45 through the annular wall of the bottle capping throat taken on line 4—4 of Fig. 3; and Figs. 5, 6 and 7 are cross-sectional views il-

lustrating the method of applying a crown cap to a bottle utilizing the capping throat of my invention.

In operating a bottle capping tool difficulty has been experienced in properly locating the crown cap with respect to the bottle which is being capped. Various forms of wire clips have been proposed heretofore for retaining the crown cap in position with respect to the capping throat. It has also been proposed to magnetize the bottle capping throat in order to suspend the crown cap in position preparatory to a bottle capping operation. The wire clip suspended on the edge of the bottle capping throat for positioning a crown cap with respect to the bottle being capped has a number of disadvantages, among which I may mention the protrusion of the wire member outside of the overall dimension of the bottle capping throat resulting in interference with the work which is normally performed in limited space. Furthermore, the wire retaining clip requires additional operations in the manufacture of the capping throat and is accordingly undesirable from the manufacturing standpoint. The magnetic type of bottle capping throat does not retain its magnetism and while effective for centering the crown cap with respect to a bottle when the bottle capping tool is new, becomes ineffective when the bottle capping tool is used for any substantial period of time.

In my invention, I so construct the bottle capping throat that a crown cap may be manually inserted therein and the cap subjected to radially inwardly directed pressure for contracting the diameter of the peripheral edge of the skirt of the cap and enabling the cap to frictionally and resiliently engage a specially prepared inner wall in the bottle capping throat whereby the cap is retained in position preparatory to a bottle capping operation. I have found that the inner wall of the bottle capping throat may be equipped with a depending skirt which is angularly disposed with respect to the upper portion of the inner wall of the bottle capping throat. The angularly disposed annular wall portion is substantially in the

shape of a truncated cone, the base diameter of which corresponds to the original diameter of the crown cap. By subjecting the crown cap to an upward movement into the 5 capping throat, the conical shaped annular wall portion of the capping throat acts upon the crown cap to effectively contract the diameter of the cap which results in the establishment of radial forces substantially 10 normal to the center line of the capping throat which serves to frictionally and resiliently maintain the crown cap in position within the capping throat preparatory for a bottle capping operation. In this way an 15 auxiliary wire retaining clip for the crown cap is wholly unnecessary and the magnetizing of the throat is entirely eliminated, and yet I have found that crown caps may be rapidly inserted in the bottle capping throat 20 by a quick upward movement between each successive bottle capping operation to insure the performance of the bottle capping tool during each capping operation. I have found the construction of capping throat of 25 my invention so effective that when the crown cap is inserted in the throat, the only practical method of withdrawing the crown cap from the throat is by performing a bottle capping operation. The principle involved 30 in the bottle capping throat of my invention resides in the deformation of the crown cap when it is initially inserted in the throat. The contracting of the size of the cap results 35 in the retention of the cap in a central position in the capping throat for the accurate alignment thereof with the top of a bottle insuring a tight seal during the bottle capping operation.

Referring to the drawings in more detail, 40 reference character 1 designates a supporting stand of a bottle capping tool which terminates in a guide head 2 at the top thereof and is provided with a supporting base 3 at the bottom thereof. A bottle capping throat 4 is carried by plunger 5 and extends through 45 the head 2. A gear system driven by hand lever 6 cooperates with the rack 7 formed on the plunger 5 enabling a downward movement to be applied to the capping throat 4 in performing a bottle capping operation upon the bottle indicated at 8. The bottle capping throat 4 has an upper wall portion 9 and a depending skirt 10 which merges into the upper wall portion 9 along a curved surface 11. The depending skirt 10 has an annular wall formed on its inner surface which is angularly disposed with respect to the axis of the bottle capping throat. The crown cap which I have illustrated at 12 and shown 50 as having crimped edges 14 has an original diameter illustrated at X. The base of the bottle capping throat at its inner diameter has a corresponding dimension X. As illustrated in Fig. 3 the inclination of the depending skirt 10 on the inner periphery of

the capping throat is such that when the crown cap 12 is inserted upwardly into the capping throat, radially inward forces are introduced which serve to decrease the effective diameter of the crown cap. That is the 70 effect of moving the crown cap 12 upwardly along the conical shaped annular depending skirt 10 is the deformation of the crown cap from its original diameter X to a smaller diameter x. This results in the introduction 75 of frictional and resilient forces by which the crown cap 12 tends to cling within the bottle capping throat. That is, the crown cap is retained in position precisely centered with the plane of the peripheral edge of the cap 80 extending substantially normal to the axis of the capping throat. Fig. 3 shows the position of the crown cap which the crown cap assumes when the cap is pressed upwardly 85 into the capping throat.

In Fig. 5 I have shown the initial bottle capping operation in which the throat 4 has received its first vertical thrust downwardly over the neck of the bottle 8. The crown cap has had its horizontally disposed top moved into the upper portion of the capping throat with the substantially vertical walls thereof extending substantially parallel to the upper annular wall 9 of the capping throat. However the lower crimped edge of 90 the cap has commenced to seat against the curved wall portion 11 within the capping throat.

In Fig. 6 the downward thrust of the bottle capping tool is shown complete as a result of which the curved surface 11 has acted upon the crimped edges 14 of the crown cap 12 and has forced such edges beneath the annular groove 15 in the neck of the bottle 8, establishing a tight seal by the compression 105 of the gasket 16 within the crown cap.

The double seal which is obtained in the capping throat of my invention is explained more fully in my Letters Patent No. 1,421, 110 698, dated July 4, 1922.

The double seal is provided by the portion 17 of the plunger 5 which is a reduced cross-section and which extends through an aperture 18 in the top of the bottle capping throat 4. The bottle capping throat 4 is provided with an annular downwardly extending edge portion 19 therein which forms with the extremity of the inwardly projecting portion 17, an anvil which strikes the central portion of the crown cap 12 as illustrated at 20, thereby forcing the cap against the neck of the bottle and depressing the center of the cap for sealing the cork filler 16 over both sides of the neck of the bottle. In order to retain the capping throat 4 in 115 position with respect to plunger 5 the projecting portion 17 of plunger 5 is swaged or expanded within the aperture 18 of the bottle capping throat 4 as represented at 21. The depth of the upper wall 9 is so selected 120

as will insure a tight outer seal of the crown cap with respect to the neck of the bottle prior to the striking of the anvil against the central portion of the cap as shown at 20.
 5 The downwardly extending angularly disposed annular skirt is selected of such length as will permit of the contraction of the cap sufficiently to introduce resilient and frictional forces for retaining the cap in position preparatory to the bottle capping operation.

The bottle capping throat of my invention has proven highly practical and successful in operation and while I have described a preferred embodiment of my invention I desire that it be understood that modifications may be made and that no limitations are intended other than are imposed by the scope of the appended claims.

20 What I claim as new and desire to secure by Letters Patent of the United States is as follows:

1. In a bottle capping tool, a bottle capping throat adapted for vertical movement toward or away from a bottle in the process of applying a crown cap to a bottle, said bottle capping throat including an annular wall structure having an upper cylindrical wall portion and a lower skirt depending therefrom, said 25 lower skirt having an angularly disposed annular wall interiorly thereof for receiving and retaining a crown cap preparatory to a bottle capping operation, said angularly disposed wall being connected through a curved wall with said cylindrical wall portion, and a downwardly depending center anvil in the top of said throat for depressing the center of the crown cap as the cap moves into the cylindrical wall portion of said throat in applying said cap to the neck of a bottle.

2. A bottle capping throat comprising an inverted cup member having a cylindrical wall including an upper wall portion and a lower depending skirt integrally connected therewith, said lower depending skirt having an angularly disposed annular wall adapted to receive a crown cap and retain said cap in position preparatory to a bottle capping operation, said angularly disposed wall being 45 connected by a curved wall with said cylindrical wall and a downwardly projecting anvil in the top of said cup member for depressing the center of said cap toward the neck of the bottle as the angularly disposed wall, said curved wall and the cylindrical wall of the cup member successively operate upon said cap.

3. A bottle capping throat comprising an inverted cup shaped member having an angularly disposed anvil centrally disposed therein and including a cylindrical wall, an annular depending skirt connected with said wall with the interior surface of said depending skirt angularly disposed with respect to the surface of said annular wall, a

curved surface interconnecting said annular wall and said angularly disposed skirt, said angularly disposed skirt operating to deform a crown cap from its original dimension when the crown cap is inserted into said inverted 70 cup shaped member preparatory to a bottle capping operation and said curved surface and annular wall operating to guide the crown cap during a bottle capping operation upon the neck of a bottle, said anvil operating 75 to depress the center of said cap into the neck of the bottle.

4. A bottle capping throat comprising an inverted cup shaped member having a center anvil therein and including a cylindrical wall portion having a predetermined fixed diameter less than the normal diameter of the peripheral edge of the skirt of a crown cap, and an angularly disposed wall having the shape of a frustum of a cone, the lower extremity of said angularly disposed wall having a diameter substantially equal to the normal diameter of the peripheral edge of the skirt of the crown cap and the upper extremity of said angularly disposed wall having a diameter less than the normal diameter of the peripheral edge of the crown cap but greater than the diameter of said cylindrical wall portion, and an intermediate curved wall interconnecting said angularly disposed wall 90 with said cylindrical wall whereby the skirt of the crown cap may be decreased in effective diameter by the advancement thereof from a position at the lower extremity of said angularly disposed wall into the cylindrical portion of said bottle capping throat and crimped around the neck of a bottle.

5. A bottle capping throat comprising an inverted cup shaped member apertured centrally of the top thereof, a plunger having 105 an end portion of reduced diameter projecting through the aperture in the top of said throat, an annular anvil integral with said cup shaped member surrounding the apertured portion thereof, the projecting end of 110 said plunger being laterally expanded in the apertured portion of said throat and terminating flush with the surface of said annular anvil, said throat having a cylindrical wall portion and a skirt portion with the walls of said skirt portion disposed in the shape of a frustum of a cone, and a curved wall interconnecting said angularly disposed wall with the cylindrical wall portion whereby a crown cap is successively operated upon 115 by inwardly directed pressure in the zones defined by said skirt portion, said curved wall portion and the cylindrical wall portion of the throat in applying the cap to the neck of a bottle in a position in which said anvil depresses the center of the cap toward the neck of the bottle in the final capping operation.

In testimony whereof I affix my signature.

HARRY J. LEBHERZ. 130
